The ornamental design for a faucet, as shown and described.

DESCRIPTION

FIG. 1 is a first side view of a faucet showing the new design;
 FIG. 2 is a second side view thereof;

FIG. 3 is a front view thereof;

FIG. 4 is a rear view thereof;

FIG. 5 is a top view thereof;

FIG. 6 is a bottom view thereof;

FIG. 7 is a top, front, right perspective view thereof; and,

FIG. 8 is a bottom, rear, left perspective view of thereof.

The broken line showing of the top of the control nozzle and the hose conduit is for the purpose of depicting portions of the article and forms no part of the claims design.
